SWITCH AND SYSTEM

Lester L. Nagel, Summit, N. J., assignor to Research Corporation, New York, N. Y., a corporation of New York

Application March 4, 1952, Serial No. 274,803

5 Claims. (Cl. 307—112)

1

This invention relates to an electric switch and an electrical system incorporating the same. More particularly the invention relates to a switch construction for selective full-wave and half-wave energization of two loads from two sources of full-wave rectified current.

An object of the invention is to provide a switch construction that is especially adapted for energization of electrical precipitation systems in which two electrical precipitators are normally separately energized with full-wave rectified alternating current from separate sources of such current and in which it is desirable to energize, on occasion, both precipitators from one of the sources of current while the other source is out of operation and disconnected from load.

Another object is to provide a switch construction that is operable to disconnect one of two current sources from its load and simultaneously to connect two loads to the other current source.

Another object is to provide a switch construction of the foregoing character that is of simple construction, reliable, and easy to operate and maintain.

Still another object is to provide in a switch construction of this sort certain features that improve safety of operation of the switch and an electrical system incorporating the switch.

These and other objects of the invention as may appear hereinafter are achieved in an electrical switch construction for elective full-wave and half-wave energization of two loads from two sources of full-wave rectified single-phase alternating current including first and second input terminals energized by alternate waves of full-wave rectified current from one source thereof, third and fourth input terminals energized by alternate waves of full-wave rectified current from a second source thereof, first and second output terminals connectible to separate loads, and switch means including simultaneously movable contact members for connecting the first and second input terminals to the first output terminal and the third and fourth input terminals to the second output terminal in one position of the contact members, for connecting the first input terminal to one of the output terminals and the second input terminal to the other output terminal while leaving the third and fourth input terminals open in a second position of the contact members, and for connecting the third input terminal to one of the output terminals and the fourth input terminal to the other output terminal while leaving the first and second output terminals open in a third position of the contact members.

2

input terminals open in a third position of the contact members.

The switch construction may also include means for selectively grounding and isolating the input terminals.

In the drawings:

Fig. 1 is a plan view of apparatus for energizing electrical precipitators including an electrical switch construction in accordance with the invention;

Fig. 2 is a front elevational view of the apparatus shown in Fig. 1;

Fig. 3 is a diagrammatic sketch of an electrical voltage transforming and rectifying circuit employed in the apparatus of Figs. 1 and 2; and

Figs. 4 to 6 are plan sketches showing various operating positions of the switch construction embodied in the apparatus of Figs. 1 and 2.

Referring to the drawings, particularly to Figs. 1 and 2 thereof, the electrical precipitator energizing apparatus shown by way of illustration has cylindrical casings 10 and 11 each housing an electrical set supplying full-wave rectified current at high voltage from single-phase alternating current of low voltage. Electrical sets for this purpose are well known in the art of electrical precipitation. However, in order to explain fully the present invention, the circuit diagram of a typical electrical set is shown in Fig. 3.

Referring to Fig. 3, the electrical set includes a power transformer 12 that steps up line voltage of 220 volts, for example, to a voltage of the order of 50,000 volts. The transformer has a primary winding 13 to which is applied through wires 14 and 15 single-phase low voltage alternating line current. The high voltage current induced in the secondary winding 16 of the transformer is conducted through wires 17 and 18 to a bridge rectifier 19, of conventional design, that employs diode rectifying tubes 20 of known construction. Rectified high voltage current is taken off from the terminals 21, 22, and 23, one half of the rectified wave appearing at terminals 21 and 23 and the alternate half appearing at terminals 22 and 23.

In the apparatus specifically illustrating the invention, the terminal 23 is grounded and the terminals 21 and 22 are insulated from ground. Other types of electrical sets may be employed such as those having mechanical rotary rectifying switches.

Referring again to Figs. 1 and 2, the insulated, or high tension terminals 21 and 22 are shown as being associated with the electrical set in casing 10 and similar high tension terminals 21'

and 22' are shown associated with the electrical set in casing 11.

The switch construction shown has a first rotary switch device designated by the general reference numeral 24 and a second rotary switch device similarly designated by the reference numeral 25.

Rotary switch device 24 has a rotor element including a shaft 26 journaled in the horizontal plate 27, the shaft being provided with a hand wheel 28 below plate 27 for manual rotation of the shaft. The shaft carries an insulating column 29 having an upper conductive metallic disc 30. Extending radially from the disc is a first conductive contact arm 31 and a second conductive radial contact arm 32 disposed 120° from the first contact arm.

The switch device also includes a complementary stator element having a first input terminal 33, a second input terminal 34 positioned 120° in the clockwise direction from the terminal 33, and a terminal 35 positioned 60° from the terminal 34 in the clockwise direction. As seen in Fig. 2, terminal 33 has an upper disc member 33a and a lower disc member 33b spaced from the upper disc member a distance approximately equal to but slightly less than the vertical thickness of the contact arm 31, so that good electrical contact is established between discs 33a and 33b and the contact arm when the arm is engaged with the terminal. Discs 33a and 33b are supported on a rod 34' carried by a stationary insulating column 35' mounted on the plate 27. Terminals 34 and 35 are constructed and supported in the same manner as terminal 33.

It will be seen that the terminals 33, 34 and 35 lie in the plane of rotation of the contact arms 31 and 32 and that the arms can make contact successively with the terminals when the rotor is turned.

The second switch device 25 is similar in construction and arrangement to the switch device 24, differing primarily only in the angular disposition of the stator terminals and rotor contact arms.

The rotor 37 of the second switch device has contact arms 38 and 39 separated by an arc of 60°. The input terminals 40 and 41 are also separated by an angle of 60° and the terminal 42 is disposed 120° from the terminal 41 in the clockwise direction. A hand wheel 43 is provided for turning the rotor 37.

Rotors 29 and 37 have crank arms 44 and 44', respectively, that are pivotally connected to a link bar 44''. The crank arms 44 and 44' are of the same length and the linkage mechanism mechanically connects the two rotors for simultaneous and equal rotation in the same direction. This linkage system is attached to the rotors below the insulating columns and is electrically isolated from the contact arms and switch terminals. By means of either of the hand wheels 28 or 43 the rotors are operated in unison.

The switch construction described hereinbefore is connected in a circuit for energizing electrical precipitators by a plurality of conductors. Output terminal 21 of the electrical set in cylindrical housing 10 is connected to switch input terminal 33 through conductors 21'' and 45. These conductors may be of any suitable construction and, as shown, are composed of pipe lengths and fittings. A surge resistor 46 is included in the conductor 21''. Output terminal 22 of the electrical set is connected to switch input terminal 34 through conductor 47 including

a surge resistor 48 and conductor 49. Terminal 35 of the switch device 24 is connected to input terminal 40 of switch device 25 through conductor 50. The switch device 24 has an output conductor 51 connected to the rotor disc 30 through a pivotal connector 52. It will also be seen that the input terminal 33 of switch device 24 is connected through conductor 53 to the terminal 42 of switch device 25.

Referring to switch device 25, the output terminal 21' of the electrical set in the cylindrical housing 11 is connected to the input terminal 40 through conductor 54, surge resistor 55, and conductor 56 while output terminal 22' is connected to input terminal 41 through conductor 57, surge resistor 58 and conductor 59. An output conductor 60 is connected to the rotor disc 61 through a pivotal connector 62.

Operation of the switch will be described with reference to Figs. 4 to 6 showing the three principal operating positions of the switch.

Referring to Fig. 4, the switch is shown in the same position it occupies in Figs. 1 and 2. Reference numerals correspond to those used to designate the same parts in Figs. 1 and 2. An electrical precipitator, conventionally shown has a grounded extended surface electrode 63 and a complementary discharge electrode 64 connected to the output conductor 51 of the switch device 24. Another electrical precipitator having a grounded extended surface electrode 65 has its complementary discharge electrode 66 connected to the output conductor 60 of the switch device 25.

With the switch parts occupying the positions shown in Fig. 4, precipitator 63, 64 is energized with full-wave rectified current from the electrical set in the housing 10 and the precipitator 65, 66 is energized with full-wave rectified current from the electrical set in housing 11. One half of a rectified wave flows from the output terminal 21 to the discharge electrode 64 through conductor 21'', terminal 33, switch arm 31, disc 30 and output conductor 51. The alternate rectified half-wave flows from the terminal 22 to the discharge electrode 64 through conductor 47, terminal 34, switch arm 32, disc 30, and output conductor 51. The two half waves are combined in the output conductor 51 180° out of phase to provide full-wave energization of the precipitator 63, 64. The electrical circuit is completed through ground from the extended surface electrode 63 to the common output terminal 23 of the electrical set.

Similarly, one half of a rectified wave from the electrical set in housing 11 flows from the output terminal 21' through conductor 54, terminal 40, switch arm 38, disc 61, and output conductor 60 to the discharge electrode 66 and the alternate half-wave flows from output terminal 22' through conductor 57, terminal 41, switch arm 39, disc 61, and conductor 60 to the discharge electrode 66. The return path is through ground. It will be noted that terminals 35 and 42 are open and that no current flows in the conductors 50 and 53.

Referring to Fig. 5, the switch rotors have been swung 60° in the clockwise direction. In this position of the switch, the electrical set in housing 10 is disconnected from load and precipitators 63, 64 and 65, 66 are energized with alternating half waves from the electrical set in the housing 11. It will be seen that input terminals 33 and 34 of the switch device 24 are open; consequently the electrical set in housing 10 is disconnected

from load, as for the purpose of making repairs, replacing tubes, etc.

One half of a rectified wave from the terminal 21' of the electrical set in housing 11 is fed to the discharge electrode 64 of the left-hand precipitator through conductors 54 and 50, terminal 35, switch arm 32, disc 30, and output conductor 51. The terminal 40 being open, no short circuiting occurs.

The alternate half of the rectified wave from the electrical set in housing 11 flows from the output terminal 22' to the discharge electrode 66 of the right hand precipitator through the conductor 57, terminal 41, switch arm 38, disc 61, and output conductor 60.

Referring to Fig. 6, showing the switch rotors advanced still another 60° in the clockwise direction, the two precipitators 63, 64 and 65, 66 are energized with alternate half waves from the electrical set in housing 10, while the electrical set in housing 11 is off load. Input terminals 40 and 41 of switch device 25, together with terminal 35 of switch device 24, are open thus effectively isolating the electrical set in housing 11 from load.

The discharge electrode 64 of the left-hand precipitator is energized with one half-wave from the terminal 22 through conductor 47, terminal 34, switch arm 31, disc 30, and output conductor 51. Also, the discharge electrode 66 of the right-hand precipitator is energized from the terminal 21 through conductors 21'' and 53, terminal 42, switch arm 39, disc 61 and output conductor 60.

The switch construction also includes an arrangement for grounding either of the electrical sets at will. Such grounding is desirable as a safety precaution when one of the sets is off load and deenergized for servicing. The grounding arrangement is shown in Figs. 1 and 2.

Referring again to Figs. 1 and 2, a grounded disc 67 is rotatably mounted on a shaft 68 provided with a hand wheel 69 for rotating the disc. The hand wheel 69 rotates the grounded disc 67 through a cam box 70 between the hand wheel and the shaft 68. The disc 67 carries a grounding arm having a radially extending section 71, a riser 72 and a horizontally extending section 73 positioned to make contact with the terminal 40 of the stator of switch device 25 when the disc 67 and arm are rotated in the clockwise direction as seen in Fig. 1.

Another grounded disc 74 is rotatably mounted on the plate 27 and has an arm 75 that makes contact with a terminal 76 on the output conductor 22' when the disc and arm are rotated counterclockwise as seen in Fig. 1. A mechanical linkage system including an arm 77 associated with the disc 67, an arm 78 associated with the disc 74, and a link 79 pivotally connected between the ends of the arms is provided to effect simultaneous operation of the grounding switches. The arms 77 and 78 are so proportioned and positioned that the switch arms 73 and 75 simultaneously make contact with the terminals 40 and 76 when the hand wheel 69 is rotated in the appropriate direction.

It will be seen that when the rotor 61 of switch device 25 is in the position shown in Fig. 6, the electrical set in housing 11 is disconnected from load. The electrical set may be deenergized and safely grounded by closing switch arms 73 and 75 with their cooperating terminals 40 and 76.

A similar grounding arrangement is provided for the electrical set in housing 10. This arrangement includes a grounding disc 80 operated

by hand wheel 81 and having an arm 82 that contacts switch terminal 33. The grounding disc 80 is connected by a linkage mechanism 83 to another rotatable grounding disc 84 having a switch arm 85 that makes contact with the terminal 86 on output conductor 22. The linkage mechanism is constructed and arranged to effect simultaneous closing and opening of the contacts 82, 83 and 85, 86.

10 When the rotor 30 of switch device 24 is in the position shown in Fig. 5, the electrical set in housing 10 is off load and may be deenergized and grounded by closing the grounding contacts.

From the foregoing description it will be seen that the present invention provides a switch construction and mechanism by which the objects of the invention are fully accomplished. It will also be seen that a variety of modifications may be made in the design and engineering of the switch construction without departing from the principles of the invention.

I claim:

1. A switch construction for selective full-wave and half-wave energization of two loads from two sources of full-wave rectified current comprising a first switch device having a stator element and a cooperating rotor element, first switch actuating means connected to said first switch device, said stator element having first, second and third terminals spaced respectively 120° and 60° apart and said rotor element having first and second arms spaced 120° apart; a second switch device having a stator element and a cooperating rotor element, second switch actuating means connected to said second switch device, said stator element having fourth, fifth and sixth terminals spaced respectively 60° and 120° apart and said rotor element having third and fourth arms spaced 60° apart; first conductor means connecting said first terminal to said sixth terminal; second conductor means connecting said third terminal to said fourth terminal; means mechanically linking said rotor elements for simultaneous rotation from a first position in which said first and second arms are in contact with said first and second terminals respectively and said third and fourth arms are in contact with said fourth and fifth terminals respectively through a second position in which said first arm is between said first and second terminals, said second arm is in contact with said third terminal, said third arm is in contact with said fifth terminal and said fourth arm is between said fifth and sixth terminals to a third position in which said first arm is in contact with said second terminal, said second arm is between said third and first terminals, said third arm is between said fifth and sixth terminals and said fourth arm is in contact with said sixth terminal; a first output terminal on the rotor of said first switch device connected to said first and second arms; and a second output terminal on the rotor of said second switch device connected to said third and fourth arms.
2. A switch construction for selective full-wave and half-wave energization of two loads from two sources of full-wave rectified current comprising a first switch device having a stationary element and a cooperating movable element, first switch actuating means connected to said first switch device, one of said elements having first, second and third terminals and the other of said elements having first and second contact members movable into contact with said terminals; a second switch device having a stationary ele-

ment and a cooperating movable element, second switch actuating means connected to said second switch device, one of said elements having fourth, fifth and sixth terminals and the other of said elements having third and fourth contact members movable into contact with said terminals; first conductor means connecting said first terminal to said sixth terminal; second conductor means connecting said third terminal to said fourth terminal; means for simultaneously moving the movable elements of said switch devices from a first position in which said first and second contact members are in contact with said first and second terminals respectively and said third and fourth contact members are in contact with said fourth and fifth terminals respectively through a second position in which said first contact member is open, said second contact member is in contact with said third terminal, said third contact member is in contact with said fifth terminal and said fourth contact member is open to a third position in which said first contact member is in contact with said second terminal, said second and third contact members are open and said fourth contact member is in contact with said sixth terminal; a first output terminal connected to said first and second contact members; and a second output terminal connected to said third and fourth contact members.

3. A switch construction for selective full-wave and half-wave energization of two loads from two sources of full-wave rectified current comprising first and second input terminals energized by alternate waves of full-wave rectified single-phase alternating current from one source thereof, third and fourth input terminals energized by alternate waves of full-wave rectified

single-phase alternating current from a second source thereof, first and second output terminals connectible to separate loads, and switch means including separate movable contact members, separate actuators for said movable contact members and means interconnecting the movable contact members for simultaneously connecting said first and second input terminals to said first output terminal and said third and fourth input terminals to said second output terminal in one position of said contact members, for connecting said first input terminal to one of said output terminals and said second input terminal to the other of said output terminals while leaving said third and fourth input terminals open in a second position of said contact members, and for connecting said third input terminal to one of said output terminals and said fourth input terminal to the other of said output terminals while leaving said first and second input terminals open in a third position of said contact members.

4. A switch construction as defined in claim 3 including means for selectively grounding and isolating said input terminals.

5. A switch construction as defined in claim 3 including means for simultaneously selectively grounding and isolating said first and second input terminals and second means for simultaneously selectively grounding and isolating said third and fourth input terminals.
